JEWELRY LOCKET

Phil S. Khalaf, 9 Gordon Drive,
Willeston Park, L.I., N.Y.

Filed Aug. 22, 1958, Ser. No. 52,341

Term of patent 7 years

(Cl. D45—15)

FIG. 1

FIG. 2

FIG. 3

FIG. 4

FIG. 1 is a front elevational view of a jewelry locket showing my new design;

FIG. 2 is a right side elevational view thereof;

FIG. 3 is a rear elevational view thereof; and

FIG. 4 is an enlarged front perspective view thereof with the locket in open position.

The cross hatch lines in FIG. 1 are engraved lines and the round indications are of tiny jewels, the lines of these jewels also being shown on the cover element of FIG. 4.

I claim:

The ornamental design for a jewelry locket, as shown and described.
